UNITED STATES PATENT OFFICE.

JOHN EDWARD ERCANBRACK, OF CHICAGO, ILLINOIS.

WATER HEATER WITH A CONSTRICTIVELY-HELD PARTITION.

Application filed December 21, 1925. Serial No. 76,779.

My present invention relates to the provision of a partition type of water heater. In such water heaters as my present invention pertains to, the water to be heated is circulated in a conduit, or pipe, the exterior whereof is subject to the action of a heating medium. Provision must be made in such pipes, or conduits, to cause the water to be introduced at one point and escape at another after it has been subjected for the maximum length of travel to the action of the heating medium. Concentrically arranged tubing, and also tubing with a partition, have heretofore been used for securing the desired circulation but, where partitions have heretofore been made, it has constituted a difficult and expensive step to install the partition. If the partition fits, or nearly fits, the interior of the tube, it is an extremely difficult matter to insert it in the tube without bending the partition, or tube, or both. If the partition is slightly undersized, as is the usual practice, it may or may not be assembled properly and, even after assembly, is liable to material displacement through the bending, or sagging, of the pipe, and the unequal expansion and contraction of the pipe and partition, and the action of the water flowing through the structure. It is, of course, highly desirable not only to realize the function of the partition as a director of circulation in the pipe but, also, have it operate for strengthening and rendering the pipe itself more rigid. I have, therefore, had for my objects the provision of a pipe, or conduit, for such heaters having a partition which not only directs the circulation in the pipe, or conduit, but, also, after assembly, forms a mechanical portion of the tube and serves to reinforce and strengthen the same. I have also had in mind the provision of an exterior head for attachment to such a partitioned pipe, or conduit, which will accomplish an economy both in manufacture and installation and will afford possibility of adaptations in assembly to meet the manifold conditions in practical installation, and will, also, permit of quick and easy cleaning of the tube, or conduit, which is a most important consideration in heaters of the type herein considered.

I attain the aforementioned objects by means of the structure illustrated in the accompanying drawings, in which—

Fig. 1 is a longitudinal central section of a water heater embodying my invention.

Fig. 2 is a fragmental schematic section illustrating the deformation of a tube.

Fig. 3 is a transverse section on line 3—3 of Fig. 1.

Figs. 4 and 5 are, respectively, front and rear views of one form of exterior head.

Fig. 6 is a perspective of one of the head securing lugs 21.

Fig. 7 is a central section of a series assembly of a plurality of my heater units.

Fig. 8 is a front elevation of the structure shown in Fig. 7; and

Fig. 9 is a front elevation of a parallel assembly of heater units.

Similar reference characters have been used throughout the several views to designate similar parts.

The tube, or conduit, is, preferably, a suitable length of commercial copper tubing 5 of the desired diameter and thickness. The inner, or remote, end of the tube 5 is closed by brazing a copper disc 6 therein. Before this disc 6 is brazed in place, however, a strip of copper plate 7 of suitable thickness, is formed having a width a sixtieth of an inch, or more, greater than the interior diameter of the tube 5, and of the length sufficiently shorter than the tube 5, so that the communicating space 8 is left at the inner, or remote, end of the tube 5, between the two sides of the plate, when the same is in position within the tube.

The tube is then deformed, or rendered slightly elliptical in section, by placing the same in an elongated vise, or other suitable mechanism, (the relation of the jaws 8^a and said tube are schematically shown in Fig. 2); and the plate 7 is introduced therein upon the greater axis 9 of the ellipse, so formed. The deforming of the tube must be done with care and should not be carried beyond the limit of elasticity of the material employed so that after the plate has been inserted, as above described, the deforming means is released which permits the tube to assume nearly its normal round form, thereby gripping the plate constrictively and holding the tube and plate in their desired adjusted relations.

With the structure assembled as described, the hydrostatic head of the water, which is admitted to circulate in the tube, assists the elasticity of the tube in pressing

the tube to its original circular shape, thereby assisting in holding the plate in position. Also, with the plate inserted in the tube, as described, and constrictively held therein, a structure is secured which is appreciably stiffer and less subject to bending, or sagging, than the tube is before the insertion of the plate.

The outer, or proximate, end of the tube 5 is flared to provide a radially extending flange 10, the outer face whereof is approximately flush with the outer end-edge of the plate 7.

The exterior head for connecting the tube 15 with the exterior system of circulation comprises a hub, or collar 11 from which extends a neck 12; there being provided at the base of the neck 12, in the outer face of the hub, an annular channel 13. Cast 20 internally of the hub and neck is a diametrical partition 14, which extends slightly beyond the hub and the corners 15, of which are shaped to fit with the flared proximate end of the tube 5. The partition 14 is centrally slotted at 14^a to receive the proximate edge of the plate 7.

To assemble this structure with a boiler, or other chamber containing a heating medium, a plate 16 of the boiler, or chamber, 30 is apertured at 17 to receive the tube 5 and, also, the tubular member, or flange 18, of a soft metal washer, the radial flange 18^a of which fits the back or rear face of the flange 10 of the tube 5. A suitable distance from 35 the edges of the aperture 17 the plate 16 is bored and tapped at three, preferably, equally spaced points 19 to receive stud bolts 20. The location of the stud bolts need not, however, be equally spaced if a rivet or 40 other feature of the boiler, or chamber, should interfere, as the lugs 21 can be positioned in any convenient place without weakening the assembly. A lug 21 is provided, one edge 21^a whereof is formed to 45 register with the neck 12; the lug being extended from said edge to permit of receiving a preferably elliptical aperture 22 for the passage of a stud bolt 20.

The elliptical shape of the apertures 22 is 50 for the purpose of an easier assembly with the stud bolt 20. Adjacent the edge 21^a is a segmental shoulder 21^b which extends into the channel 13. Also, a yoke-shaped 55 depending flange 21^c is formed about the aperture 21 for pressing against the edge of the hub 11, and additionally reinforcing and strengthening the lug. A nut 23 is screwed down on the stud bolt 20 and down 60 on top of the lug 21, thereby drawing the hub 11 and the flange 10 and the washer 18^a together and in contact with the plate 16.

The head in front of the neck 12 is produced into a substantially rectangular member with hubs 24 and 25 on its right and 65 left sides; also, hubs 26 and 27, on, respec-

tively, its bottom and top, and, preferably, two adjacent and confluent hubs 28 and 29 upon the face, or proximate, side. Each of the aforesaid hubs are bored and tapped to receive pipe connections, or plugs, as 70 may be required in any particular installation. The partition 14 is extended up and around the openings in the lateral hubs 24 and 25 and ends in connection with the interior of the head between the bores in the confluent hubs 28 and 29. In the highest portion of the partition 14 is a bleed hole, or air vent 14^a, to prevent the trapping of air in the lower compartment of the head.

The assembly of the individual units of 80 the heater in series is shown in Figs. 7 and 8. In series assembly, the water to be heated passes successively through the several units in the installation, and in this form of series assembly the cold water inlet is made with either hub 24 or 25, the opposite hub being plugged or closed with plug 25^a. The hub 26 is closed with a plug 26^a and a nipple 27^a connects hub 27 of the first head 85 of the assembly with hub 26 of an adjacent head. If this adjacent head be an intermediate head both hubs 24 and 25 are plugged and its hub 27 is likewise connected by nipple 27^b with a hub 27 of the next adjacent head. If the next adjacent head is the last 90 head in the assembly, hub 26 is plugged and the hot water supply is taken from either hub 24 or 25, the hub opposite to the hot water lead being plugged. In this manner, 95 as clearly seen in Fig. 7, the circulation will be successively through the respective units of the heater.

If, however, a parallel arrangement is desired the cold water connection is made 100 with either hub 24 or 25 and the hot water connection is made with each of the hubs 27. Connections between heads in a parallel assembly are made by nipples 24^a running 105 between hubs 24 and 25, so that the cold water enters each section without having to transverse the heating element of the other sections and is delivered from each section 110 directly to the hot water service pipe.

Having described my invention, what I 115 claim is new and desire to secure by Letters Patent, is

1. A tube for water heaters transversely deformed within the limit of elasticity of the material of which the tube is composed and a partition disposed within and constrictively held in position by the elasticity of said tube.

2. A tube transversely deformed within the limit of elasticity of the material of which the tube is composed and a partition disposed within and constrictively held in position by the elasticity of said tube.

3. A conduit for securing to and fro fluid circulation comprising a tube closed at one 120 end and transversely deformed within the 125

limit of elasticity of the material of which said tube is composed and a partition extending longitudinally of said tube to a point spaced from the closed end thereof, 5 said partition being constrictively held within said tube by the elasticity thereof and the pressure of the fluid circulating therein.

4. A method of forming partitioned tubes consisting of transversely deforming the

tubes within the limit of elasticity of the 10 material of which the tubes are formed, inserting partitions of greater width than the initial diameter of said tubes upon the greater axis of the ellipse so formed, and releasing the deforming means whereby said partitions are constrictively held. 15

J. EDWARD ERCANBRACK.
